ORGAN CONSOLE

Winsor D. White, Jr., Blowing Rock, Calif., assignor to D. H. Baldwin Company, Cincinnati, Ohio, a corporation of Ohio

Filed June 30, 1966, Ser. No. 2,872

Term of patent 14 years

(Cl. D56—2)

Fig. 1

Fig. 2

FIG. 1 is a perspective view of an organ console, embodying my new design.

FIG. 2 is a partial perspective view thereof with the fallboard being shown in closed position.

The dominant features of my design reside in the portions shown in full lines. The side of the organ console not shown is the same as the side shown. The conventional manuals and conventional pedal clavier are shown by means of broken lines.

I claim:

The ornamental design for an organ console, substantially as shown and described.
